UNITED STATES PATENT OFFICE

2,208,203

LINE INDICATING DEVICE

Paul O. Unger, Elmhurst, Ill., assignor to Wilson-Jones Company, Chicago, Ill., a corporation of Massachusetts

Application September 3, 1937, Serial No. 162,259

4 Claims. (Cl. 120—33)

This invention relates to a loose-leaf binder adapted to facilitate comparison or computation of various data noted on a plurality of sheets mounted in the binder.

5 It is an object of this invention to provide a loose-leaf binder of the type described in my prior Patent No. 1,979,814 granted November 6, 1934, with means for adjusting the angularity of the line guide and maintaining the line guide in proper position to facilitate reading of data written or typed on the sheets. Other objects of this invention will become apparent upon reading the following description taken in conjunction with the accompanying drawings, in which—

15 Figure 1 is a perspective view of the loose-leaf binder in open or reading position;

Figure 2 is an end elevation showing the binder in closed position;

20 Figure 3 is a detail perspective view of the line guide;

Figure 4 is a top plan view of the structure upon which the line guide is mounted;

25 Figure 5 is a cross sectional view taken along the line V—V of Figure 4, and

Figure 6 is a cross sectional view taken along the line VI—VI of Figure 4.

In the drawings the reference numerals 2 and 30 3 indicate a pair of cover members hingedly connected to opposite edges of a back section 4, as indicated at 5 and 6, respectively, Figure 1. A conventional ring metal 7 carrying a plurality of divided rings 8 is secured to the back section 4 by any suitable means. The ring metal 7 is provided at each end with a trigger 9 operable to open and close the divided rings 8.

35 A plurality of sheets 10, each shorter than the binder, is arranged on the divided rings 8 in overlapping relationship. Although only one 40 bank of sheets is shown, it will be understood that the ring metal is capable of holding several banks of sheets with any bank exposed for reference. A pair of sheet lifters 11 is carried on the divided rings 8 adjacent the covers 2 and 3 so that one pair of sheet lifters is under the 45 sheets 10 regardless of the position of the sheets. If desired, a single sheet lifter extending the length of the binder may be substituted for each 50 pair of sheet lifters 11. The sheet lifters each have one edge 12 which extends at an angle to the rest of the lifter and acts as an aligning member to keep the sheets 10 in orderly arrangement so that each sheet is parallel to every other sheet. The sheet lifters are preferably formed of fiber 55 and perform the usual function of facilitating

movement of the sheets from one side of the binder to the other.

The cover member 3 has a pair of straps 13 secured thereto by means of rivets or eyelets 14. The free end of each strap 13 is provided with glove fastener buttons 15 and 16 on opposite sides of the strap. The cover member 2 is provided with a pair of glove fastener studs 17 on its outer face adapted to be engaged by the buttons 15 to hold the binder in closed position as indicated in Figure 2. The inner surface of the cover member 2 is provided with a pair of glove fastener studs 18 adapted to be engaged by the buttons 16 to hold the binder in open or reading position, as shown in Fig. 1.

15 A bracket 19 is pivotally secured to the cover member 2, which acts as a supporting member for the line indicating device, as indicated at 20. A rod 21 has one end rigidly secured to the bracket 19. The other end of the rod is rigidly 20 secured to a rod support 22. A bracket 23 is secured to the cover or supporting member 2 in any suitable manner. The bracket 23 is provided with a pair of upstanding ears 24. A screw 25 is mounted in the apertures of ears 24 so as 25 to rotate without moving axially relative to the bracket. The screw 25 is provided with an enlarged head 26 to facilitate rotation of the screw.

The rod support 22 is provided with a pair of screw threaded apertures and is mounted on the 30 screw between the ears 24. Rotation of the screw 25 moves the rod support and the rod in either direction around the pivot 20.

A line guide support 27 is slidably mounted on the rod 21. A knob 27' facilitates manipulation 35 of said line guide support. The support 27 has two curled extensions 28 and 29 to retain it on the rod. A flat spring member 30 (Figure 4) welded to the back of the member 27 has one end 31 extending between the curled extensions 40 28 and 29. The end 31 of the flat spring member 30 is curled in the direction opposite to the curl of the extensions 28 and 29. The end 31 of the flat spring 30 contacts with the rod 21 with sufficient friction to retain the line guide support 45 in any position on the rod 21 in which it is placed. The frictional contact of the spring 30 against the rod 21 also retains the line guide support 27 at any angular position of rotation about the rod 21 in which it may be placed. 50 This enables the operator to swing the guide 34 out of the way with one hand by pulling outwardly on knob 27' and then to turn any desired number of sheets from one side of the binder to the other without the necessity of 55

holding the line guide support 27 out of the way. The frictional force of the spring 30 against the rod 21 is not sufficient, however, to interfere to any appreciable extent with the sliding movement of the line guide support 27 on the rod 21.

5 A key 32 is welded or riveted to the line guide support 27. A pair of studs 33 is secured to the key 32. Each stud 33 is provided with an enlarged head 33' spaced from the key 32. A line guide 10 34 is provided adjacent one end with a pair of pear shaped apertures 35 adapted to engage the studs 33. A pair of strips 36 is welded or riveted to the line guide to form a keyway cooperating with the key 32 to keep the line guide from sagging. The studs 33 and apertures 35 comprise 15 means for quickly and readily attaching the line guide to the line guide support or detaching it therefrom. The screw 25 permits adjustment of the rod 21 to regulate the angularity of the line 20 guide 34. The line guide 34 is provided at its free end with a loop 37 to space the free end of the line guide the same distance from the cover member 2 as the end secured to the support 27. This structure maintains the line guide truly 25 parallel to the data on the sheets and facilitates the reading of said data.

While I have described a preferred embodiment of my invention in considerable detail, it will be understood that the description thereof is illustrative rather than restrictive, as many details 30 may be modified or changed without departing from the spirit or scope of the invention. Accordingly, I do not desire to be restricted to the exact construction described except as limited by 35 the appended claims.

I claim:

1. In a line indicating device, a supporting member, a rod pivotally secured at one of its ends to said supporting member, the other end of said rod being movably secured to said supporting member, means to move said rod about said pivot point, and a line guide support mounted on said rod.

2. In a line indicating device, a supporting member, a rod pivotally secured at one of its ends to said supporting member, a bracket mounted on said supporting member, the other end of said rod being mounted on said bracket, and screw means for moving said rod relative to said bracket.

3. A line indicating device including a supporting member, a rod secured adjacent one end of said supporting member, a line guide support mounted on said rod, and means for moving said rod relative to said supporting member to adjust 20 the angularity of a line guide mounted on said support.

4. In a line indicating device, a supporting member, a rod secured adjacent one end of said supporting member in spaced relationship thereto, a line guide support mounted on said rod, a line guide removably secured to said support, means on the unsecured end of said line guide to space said unsecured end of said line guide from said supporting member, and means for 30 moving said rod relatively to said supporting member to adjust the angularity of said line guide.

PAUL O. UNGER. 35
